UNITED STATES PATENT OFFICE.

GEORGE MERTEL, OF BROOKLYN, NEW YORK.

PINWHEEL NOVELTY.

1,320,262.

Specification of Letters Patent.

Patented Oct. 28, 1919.

Application filed November 27, 1918. Serial No. 264,363.

To all whom it may concern:

Be it known that I, GEORGE MERTEL, a citizen of the United States, and a resident of the city of New York, borough of Brooklyn, in the county of Kings and State of New York, have invented a new and Improved Pinwheel Novelty, of which the following is a full, clear, and exact description.

The object of the invention is to provide 10 a new and improved pin wheel novelty arranged to attractively display the national flag or other similar patriotic emblems or devices. Another object is to permit of readily attaching the novelty to a coat, hat 15 or other article of wear, or to a stick or other supporting device, to expose the pin wheel novelty to the action of the wind with a view to rotate the pin wheel in the usual manner.

20 With these and other objects in view, the invention consists of certain novel features of construction, as hereinafter shown and described and then specifically pointed out in the claims.

25 A practical embodiment of the invention is represented in the accompanying drawings forming a part of this specification, in which similar characters of reference indicate corresponding parts in all the views.

30 Figure 1 is a face view of the pin wheel novelty;

Fig. 2 is a side elevation of the same; and Fig. 3 is a cross section of the wheel.

The propeller or pin wheel 10 is mounted 35 to turn on a horizontally disposed pivot 11 held on a support or frame 12 adapted to be attached to a coat, vest, hat or other article of personal wear. For this purpose the pivot 11 is preferably extended at the 40 rear of the support to form a downwardly extending attaching pin 13, but I do not limit myself to this particular means for fastening the pin wheel novelty to a garment, stick or other device. The propeller 45 or pin wheel 10 is provided with propeller blades set at an angle to the axis of the wheel to cause the latter to turn on the wind striking the wheel. One of the blades is over-balanced relative to the remaining 50 blades and for this purpose the back of this overbalanced blade is provided with a weight 15 and hence when the wheel comes to a standstill this overbalanced blade is in lowermost position, as indicated in the 55 drawings. The overbalanced blade is provided on its face with an ornamentation 16,

preferably in the form of a United States flag, and a similar face ornamentation 17 is arranged on the blade diametrically opposite the overbalanced blade so that when 60 the pin wheel 10 comes to a stop the United States flags 16 and 17 are displayed at the bottom and top of the pin wheel. The remaining blades are provided with face ornamentations 18, such as the flags of the Al- 65 lies, for instance, but it is expressly understood that I do not limit myself to the flag 70 ornamentations as other face ornamentations, such as portraits or other emblems, may be used, but the face ornamentations 16 and 17 of the overbalanced blade and the one diametrically opposite are similar, while the face ornamentations 18 of the remaining blades are dissimilar.

In order to enhance the display effect, use 75 is made of a pointer 20, preferably in the form of a hand, and forming a turned up portion of the lower end of the support 12, the pointer being at the bottom of the wheel 10 so as to point directly to the United 80 States flag 16 as soon as the pin wheel comes to a rest as above explained. The two similar face ornamentations 16 and 17 are used on diametrically opposite blades, of which one is overbalanced so that in case the over- 85 balanced blade should come to a stop when in uppermost position then the pointer 20 still points at the face ornamentation 17 representing the United States flag.

Having thus described my invention, I 90 claim as new and desire to secure by Letters Patent:—

1. As an article of manufacture, a pin wheel novelty, comprising a support having attaching means on its back and a pin wheel 95 mounted to turn on the support, the pin wheel having blades of which one is overbalanced relative to the other blade, the overbalanced blade and the one diametrically opposite having similar face ornamentations produced thereon and the remaining blades having dissimilar face ornamentations.

2. As an article of manufacture, a pin wheel novelty, comprising a support pro- 105 vided with means for attaching the novelty to an article of wear, a pin wheel mounted to turn on the said support and provided with blades having face ornamentations, one of the blades being over-balanced relative to the other blades, the said overbalanced blade and the one diametrically op-

posite the same having their face ornamentations similar and the other blades having their face ornamentations dissimilar, and a pointer integral with the support at the bottom of the pin wheel.

3. As an article of manufacture, a pin wheel novelty, comprising a frame having its upper and lower ends bent and extend-

ing toward each other, the lower bent end being in the form of a pointer, a pivot in the upper bent end extended to the back of the frame to form an attaching pin, and a pin wheel mounted on the pivot and having ornamentations produced on the blades, one of the blades being weighted.

GEORGE MERTEL.
